WINDOW WELL COVER

Armel U. Faubion, Adams County, Colo., assignor to Related Sales, Inc.

Filed May 11, 1964, Ser. No. 79,902

Term of patent 14 years

(Cl. D13—1)

FIG. 1

FIG. 2

FIG. 3

FIG. 4

FIG. 1 is a perspective of a window well cover embodying my new design;

FIG. 2 is an end elevation of the window well cover of FIG. 1;

FIG. 3 is a rear elevational view of the window well cover; and

FIG. 4 is a top plan view of the window well cover.

I claim:

The ornamental design for a window well cover, substantially as shown.
